HANDLE COLUMN FOR A BOAT

Makoto Nakajima, Kobe-shi, and Katuichi Kato, Miki-shi, Japan, assignors to Kawasaki Jukogyo Kabushiki Kai-sha, Kobe-shi, Hyogo-ken, Japan

Original design application Nov. 13, 1973, Ser. No. 415,346. Divided and this application Nov. 21, 1975, Ser. No. 634,184

Claims priority, application Japan May 26, 1973

Term of patent 14 years

Int. Cl. D12—99

U.S. Cl. D12—174

FIG. 1 is a perspective view of a handle column for a boat showing our new design, a boat being shown in phantom lines merely for illustrative purposes;

FIG. 2 is a right side elevational view of the handle column shown in FIG. 1;

FIG. 3 is a top plan view thereof;

FIG. 4 is a rear elevational view thereof;

FIG. 5 is a front elevational view thereof; and

FIG. 6 is a bottom plan view thereof.

This is a division of application Ser. No. D. 415,346, filed Nov. 13, 1973.

We claim:

The ornamental design for a handle column for a boat, as shown and described.
